(57) **CLAIM**

The ornamental design for a vehicle bed rail garnish, as shown and described.

DESCRIPTION

FIG. 1 is a perspective view of a vehicle bed rail garnish showing our new design;

FIG. 2 is a top plan view thereof;

FIG. 3 is a side elevational view thereof; and,

FIG. 4 is an end elevational view thereof.

The broken line showing of the connection aperture in FIG. 3 is for illustrative purposes only and forms no part of the claimed invention.
